UNITED STATES PATENT OFFICE.

ZACHARY E. RUSSELL, OF SAUK RAPIDS, MINNESOTA, ASSIGNOR TO CLYDE W. WARREN,
OF SAUK RAPIDS, MINNESOTA.

CURTAIN-ANCHORING DEVICE.

1,225,060.

Specification of Letters Patent.

Patented May 8, 1917.

Application filed January 28, 1916. Serial No. 74,776.

To all whom it may concern:

Be it known that I, ZACHARY E. RUSSELL, a citizen of the United States, residing at Sauk Rapids, in the county of Benton and

5 State of Minnesota, have invented certain new and useful Improvements in Curtain-Anchoring Devices; and I do hereby declare the following to be a full, clear, and exact description of the invention, such as will 10 enable others skilled in the art to which it appertains to make and use the same.

My invention relates to rolling curtains or shades, such as woven slat porch curtains which are easily raised and lowered by 15 means of a cord that encircles the lower portion thereof, and the invention has for its object to provide a simple and efficient anchoring device for holding down the lower portions of the curtains or shades, so that 20 they cannot flap around even under wind pressure. To the above ends, generally stated, the invention consists of the novel devices and combinations of devices herein-after described and defined in the claims.

25 In the accompanying drawings which illustrate the invention, like characters indicate like parts throughout the several views.

Referring to the drawings:

Figure 1 is a view in elevation showing 30 two porch curtains of the character above indicated and showing my improved anchoring device applied thereto; and

Fig. 2 is a section taken on the line $x^2 x^2$ of Fig. 1, some parts being broken away, and 35 showing the parts on a larger scale than in Fig. 1.

The numeral 1 indicates the framework in the opening of a porch and the numeral 2 indicates woven slat curtains anchored to the 40 top of the said opening, as shown, by means of a clamping bar 3 and coöperating fastening device, not shown. The lower portions of these curtains are adapted to be independently lowered to independently adjust the 45 curtain, by means of the customary adjusting cords 4, which cords are arranged in pairs for each curtain and anchored at their upper ends. The said cords 4 are then brought under the lower rolled portions of 50 the respective curtains and are passed upward over suitable anchor guides, such as sleeve 5 in yokes 6 attached to the fixed bar 3, by means of screw eyes 7, or the like.

This is customary, the loose ends of the curtain lifting and adjusting cords 4 may be 55 fastened to cleats 8 on the sides of the porch opening 1, or elsewhere.

In the application of my improved anchoring device, rings 9 are hung on the lower looped portions of the cords 4 just below the 60 rolled lower portions of the curtains, and anchoring cords 10 are applied to the said rings. In the arrangement illustrated, the said anchoring cord 10, at one end, is secured to the left hand ring 9, is passed downward 65 through an anchored guide ring 11, thence upward through another anchor guide ring 12, thence upward through the second ring 9, thence downward and again through the anchor guide ring 12 and through another 70 anchor guide ring 13, thence upward through the left hand guide ring 9 of the second curtain, thence again downward and through the said anchor guide ring 13, thence upward through a fourth anchor guide ring 14 and 75 through the right hand guide ring 9 of the said second curtain, thence downward and again through the said anchor guide ring 14, and from thence to an anchoring cleat 15, or other suitable fastening device. By this ar- 80 rangement, as is evident, regardless of the different adjustments of the two curtains, the lower edges of the said curtain may be drawn tightly down and securely held, by the single anchoring cord 10. Of course, this ar- 85 rangement of the anchoring cord may be used independently on different curtains, and on the other hand, it may be extended to a large number of curtains, so that, for example, all of the curtains of a porch may be anchored 90 by a single anchoring cord. This arrangement is not only extremely simple and highly efficient, but affords a device that may be very quickly and easily operated and which, furthermore, is of very small cost. 95

What I claim is:

1. The combination with a suspended curtain and a pair of adjusting cords embracing the lower portion thereof for rolling the same and holding the curtain in different ad- 100 justments, and an anchoring cord passed alternately through guides on the lower portions of said adjusting cords and through anchor guides located below the curtain.

2. The combination with a suspended cur- 105 tain and a pair of adjusting cords embracing

the lower portion thereof for rolling the same and holding the curtain in different adjustments, of guide rings on the lowermost portions of said adjusting cords, and an anchoring cord passed alternately through said guide rings and through anchored guides located below the same.

In testimony whereof I affix my signature in presence of two witnesses.

ZACHARY E. RUSSELL.

Witnesses:

R. S. NEILS,
LIZZIE VOLKMANN.
